UNITED STATES PATENT OFFICE.

EMIL LUCHSINGER, OF BERLIN, GERMANY, ASSIGNOR TO N. V. INSTITUUT VOOR AERO- EN HYDRODYNAMIEK, OF AMSTERDAM, NETHERLANDS, A DUTCH COMPANY.

STEERING ARRANGEMENT.

Application filed August 6, 1923. Serial No. 656,105.

To all whom it may concern:

Be it known that I, EMIL LUCHSINGER, a citizen of the Swiss Confederation, and residing at Berlin, Germany, have invented 5 certain new and useful Improvements in a Steering Arrangement, of which the following is a specification.

Steering arrangements such as rudder arrangements for vessels and aircraft, airships and flying machines, in which the main rudder is adjusted by means of at least one auxiliary rudder with the aid of the current, have a coupling gearing so arranged between main rudder and auxiliary rudder that the 15 latter is returned to its position of rest as soon as the main rudder has completed its prescribed movement. Besides, said gearing serves, in the event of any undesired movements of the main rudder caused by the current, to effect such a movement of the auxiliary rudder with reference to the main rudder that the latter is returned to its prescribed position, e. g., normal position for going in straight direction, or steering position. Finally, said gearing is to effect the corresponding movements of the main rudder with reference to the auxiliary rudder if, when going astern, the main rudder is reversed for 180°.

To attain these effects, between main rudder and auxiliary rudder a transmission gearing to "fast" is so arranged that a small angular turning of the main rudder results in a large angular turning of the auxiliary rudder. If, when going astern, the main rudder is reversed, said gearing, in a preferred form of construction, is so arranged that the auxiliary rudder executes an oscillatory movement with reference to the main rudder, and that in such a way that in proximity to the working position a small movement of the main rudder results in a large movement of the auxiliary rudder, while, when surpassing the position "close on board", the ratio of transmission from the main rudder to the auxiliary rudder results only in a trifling angular turning of the auxiliary rudder in the same direction or in a reversal of the auxiliary rudder movement.

Generally, the gearing of the rudder arrangement will be mounted on the rudder head, so that it moves with the rudder, while the driving mechanism of the direction governor that is adjusted from a place on the vessel, is also carried by the rudder head

but stationary with reference to the vessel, though resilient. The direction governor in the present instance is constituted by a disc 11 (see Fig. 1) which indicates the steering direction in which the auxiliary 60 surface should guide the main surface and in which the auxiliary surface should hold the main surface.

The present invention has for its object to improve steering arrangements of such a 65 rudder arrangement for vessels and airships, so as to combine the same with an extremely simple gearing that suits the above mentioned requirements.

The accompanying drawing represents one 70 preferred form of the construction of the improved rudder arrangement: Fig. 1 is a sectional elevation of the same, while Fig. 2 is a cross-section on the line $x-x$ of Fig. 1.

1 designates the shaft of the main rudder 75 20, said shaft being freely turnable in the framing of the vessel, and 2 is the shaft of the auxiliary rudder 21, said latter shaft being centrally mounted in said main rudder shaft. The latter carries on its top end a 80 fixed disc 3 forming the bottom of a casing 4, which thus is adapted to participate in the movements of the main rudder. The cover 5 of said casing is mounted over a ring 6 which is integral with a box 6' that is stationary in the vessel. The auxiliary rudder shaft 2 can be driven from the bridge or other commanding place of the vessel by means of a rotary axle 7, which transmits its movement to the axle 10 of a cam-disc 85 90 11 in the upper part of the casing 4 through a worm gearing 8, 9 in the box 6'. Said cam-disc 11 is so designed that it suits the desired movements of the auxiliary rudder 95 21: Thus, for instance, from the circumference 95 of a circle the radii of the circle are increased or decreased respectively for the ordinates of a periodical curve, corresponding to which the ratio of the angular speed between main plane and auxiliary plane is 100 to be determined.

In the example illustrated, the cam-disc 11 is designed symmetrically with reference to two axes $a-a$ and $b-b$, located at right angles to one another.

The cam-disc 11 forms preferably a double disc in order to avoid a separate contacting contrivance for the rollers sliding thereon. The cam-disc gearing thus comprises two cam races 12 and 13, each being in contact 105 110

with a roller 15 or 16, said rollers being mounted on the ends of a knee-lever 14. The discs which can be arranged symmetrically to two axes which are at right angles to each other, such, for example, as $c-c$, $d-d$, of disc 3, are displaced with reference to one another as concerns their phases, the angle of the knee-lever 14 being correspondingly determined (Fig. 2). The 10 trunnion 17 of the knee-lever 14 is mounted in the casing 4 and transmits its movements received from the cam-disc 11, to the auxiliary rudder shaft 2 through the medium of a transmission gearing 18 of any 15 appropriate type in the lower part of the casing 4. If said driving mechanism of the auxiliary rudder shaft 2 is at rest and the freely turnable main rudder is displaced for instance by a change of the current, the 20 main rudder shaft 1 and the casing 4 fixed thereon are turned. The knee-lever 14 fulcrumed in the latter at 17 participates in said movement and, consequently, the rollers 15, 16 are guided along the cam races of the 25 cam-disc 11 which is then in fixed position. Thus, therefore in this case, the trunnion 17 is set in rotation and a corresponding counter-movement of the auxiliary rudder 21 is produced through the medium of the 30 transmission gearing 18. If, as it normally happens, the control of the auxiliary rudder and the self movement of the main rudder take place at the same time, the steps above described coincide with one another. 35 Thus, the operation of the driving mechanism from the direction indicator results in the adjustment of a cam race in contact with an oscillatory roller-lever, the trunnion of which is rigidly connected with the 40 main rudder.

The construction illustrated in the example, in which a double cam-disc 12, 13 is employed in connection with a knee-lever 14 having rollers 15, 16 in contact with said 45 disc, represents a preferred form of the improved rudder arrangement. By appropriately designing the cam races of said cam-disc, it is possible to control and to determine in a perfectly free way the dependence 50 of the two rudder movements upon one another. Thus, within the zero position of the auxiliary rudder the design of the cam races must be so chosen that by a ratio of transmission from "slow" to "fast" an 55 effective rudder angle can be rapidly attained when driving the auxiliary rudder as well as at an automatic counter-movement of the same, and within the largest rudder movements in such a way that as little expenditure of power as possible is required 60 for the active drive. Besides, the normal requirements of such gearings can also be easily accomplished. Thus, for instance, the correct position of the auxiliary rudder 65 relatively to the main rudder and the ship

may be obtained when the ship's direction is reversed and the main rudder is turned 180°. Furthermore, in operating the main rudder for steering toward one side, the 70 position of the auxiliary rudder with respect to the main rudder will be symmetrical to that occupied by the auxiliary rudder when the main rudder is operated to an equal angle for steering toward the other side. 75

What I claim, is:

1. In a steering arrangement in combination, a main plane, at least one auxiliary plane adapted to adjust the latter with the aid of the current, and an intermediary 80 gearing comprising at least two parts, namely a cam race and a sliding contrivance in contact therewith, and adapted to produce the relative movement to be executed by the auxiliary plane with reference to the main plane, one of said parts adapted to be adjusted from the steering device and another part to participate in the movement of the 85 main plane.

2. In a steering arrangement: in combination, a main plane, at least one auxiliary plane adapted to adjust the latter with the aid of the current, and an intermediary gearing comprising at least two parts, namely a cam-disc and a sliding contrivance in contact therewith, and adapted to produce the relative movement to be executed by the auxiliary plane with reference to the main plane, one of said parts adapted to be adjusted from the steering device and another 95 part to participate in the movement of the main plane.

3. In a steering arrangement in combination, a main plane, at least one auxiliary plane adapted to adjust the latter with the aid of the current, and an intermediary gearing comprising at least two parts, namely a cam race and a sliding contrivance in contact therewith, and adapted to produce the relative movement to be executed by the auxiliary plane with reference to the main plane, one of said parts adapted to be adjusted from the direction governor and another part to participate in the movement of the 100 main plane.

4. In a steering arrangement: in combination, a main plane, at least one auxiliary plane adapted to adjust the latter with the aid of the current, and an intermediary gearing comprising at least two parts, namely a cam-disc and a sliding contrivance in contact therewith, and adapted to produce the relative movement to be executed by the auxiliary plane with reference to the main plane, one of said parts adapted to be adjusted from the direction governor and another part to participate in the movement of the 110 main plane.

5. In a steering arrangement: in combination, a main plane, at least one auxiliary 120

aid of the current, and an intermediary gearing comprising at least two parts, namely a cam-disc and an oscillatory roller-lever in contact therewith, and adapted to produce the relative movement to be executed by the auxiliary plane with reference to the main plane, one of said parts adapted to be adjusted from the direction governor and another part to participate in the movement of the main plane.

15. In a steering arrangement: in combination, a main plane, at least one auxiliary plane adapted to adjust the latter with the aid of the current, and an intermediary gearing comprising at least two parts, namely a cam-disc and an oscillatory roller-lever fulcrumed on the main plane, and adapted to produce the relative movement to be executed by the auxiliary plane with reference to the main plane, one of said parts adapted to be adjusted from the direction governor and another part to participate in the movement of the main plane.

16. In a steering arrangement: in combination, a main plane, at least one auxiliary plane adapted to adjust the latter with the aid of the current, and an intermediary gearing comprising at least two parts, namely a cam-disc and an oscillatory roller-lever in contact therewith having its trunnion mounted on the main plane and coupled with the auxiliary plane, and adapted to produce the relative movement to be executed by the auxiliary plane with reference to the main plane, one of said parts adapted to be adjusted from the direction governor and another part to participate in the movement of the main plane.

17. In a steering arrangement: in combination, a main plane, at least one auxiliary plane adapted to adjust the latter with the aid of the current, and an intermediary gearing comprising at least two parts, namely a cam-disc and an oscillatory roller-lever having its trunnion mounted on the main plane and coupled with the auxiliary plane shaft that is centrally located in the main plane shaft, and adapted to produce the relative movement to be executed by the auxiliary plane with reference to the main plane, one of said parts adapted to be adjusted from the direction governor and another part to participate in the movement of the main plane.

18. In a steering arrangement: in combination, a main plane, at least one auxiliary plane adapted to adjust the latter with the aid of the current, and an intermediary gearing comprising at least two parts, namely a double cam-disc and an oscillatory roller-lever in contact therewith, and adapted to produce the relative movement to be executed by the auxiliary plane with reference to the main plane, one of said parts adapted to be adjusted from the direction governor

and another part to participate in the movement of the main plane.

19. In a steering arrangement: in combination, a main plane, at least one auxiliary plane adapted to adjust the latter with the aid of the current, and an intermediary gearing comprising at least two parts, namely a double cam-disc with displaceable phases of the single discs and a knee-lever of which the angle corresponds to the phase angle of the discs, and adapted to produce the relative movement to be executed by the auxiliary plane with reference to the main plane, one of said parts adapted to be adjusted from the direction governor and another part to participate in the movement of the main plane.

20. In a steering arrangement: in combination, a main plane, at least one auxiliary plane adapted to adjust the latter with the aid of the current, driving mechanism comprising a worm-gearing for an adjustment of said auxiliary plane, and an intermediary gearing comprising at least two parts, namely, a double cam-disc with displaceable phases of the single discs and an oscillatory knee-lever in contact therewith, and adapted to produce the relative movement to be executed by the auxiliary plane with reference to the main plane, one of said parts adapted to be adjusted by the direction governor and another part to participate in the movement of the main plane.

21. In a rudder arrangement for vessels and aircraft: in combination, a main rudder, at least one auxiliary rudder adapted to adjust the latter with the aid of the current, driving mechanism for an adjustment of said auxiliary rudder, and an intermediary gearing comprising at least two parts, namely a double cam-disc with displaced phases of the single discs and an oscillatory knee-lever in contact therewith, and adapted to produce the relative movement to be executed by the auxiliary rudder with reference to the main rudder, said cam-disc serving as direction governor and adapted to be adjusted from the vessel and said knee-lever fulcrumed on said main rudder and adapted to participate in the movement of the latter.

22. In a rudder arrangement for vessels and aircraft: in combination, a main rudder, at least one auxiliary rudder adapted to adjust the latter with the aid of the current, driving mechanism for an adjustment of said auxiliary rudder, and an intermediary gearing comprising at least two parts, namely a double cam-disc with displaced phases of the single discs and symmetrical with reference to at least one axis and an oscillatory knee-lever in contact therewith, and adapted to produce the relative movement to be executed by the auxiliary rudder with reference to the main

rudder, said cam-disc serving as direction governor and adapted to be adjusted from the vessel and said knee-lever fulcrumed on said main rudder and adapted to participate 5 in the movement of the latter.

23. In a rudder arrangement for vessels and aircraft: in combination, a main rudder, at least one auxiliary rudder adapted to adjust the latter with the aid of the current, driving mechanism for an adjustment of said auxiliary rudder, and an intermediary gearing comprising at least two parts, namely a double cam-disc with displaced phases of the single discs and sym- 10 metrical with reference to two axes and an oscillatory knee-lever in contact therewith, and adapted to produce the relative movement to be executed by the auxiliary rudder with reference to the main rudder, said 15 cam-disc serving as direction governor and adapted to be adjusted from the vessel and said knee-lever fulcrumed on said main rudder and adapted to participate in the movement of the latter.

24. In a rudder arrangement for vessels and aircraft: in combination, a main rudder, at least one auxiliary rudder adapted to adjust the latter with the aid of the current, driving mechanism for an adjustment 20 of said auxiliary rudder, and an intermediary gearing comprising at least two parts, namely a double cam-disc with displaced phases of the single discs and sym- 25 metrical with reference to two axes and an oscillatory knee-lever in contact therewith, and adapted to produce the relative movement to be executed by the auxiliary rudder with reference to the main rudder, said cam-disc serving as direction governor and adapted to be adjusted from the vessel and said knee-lever fulcrumed on said main rudder and adapted to participate in the movement 30 of the latter.

25. In a rudder arrangement for vessels and aircraft: in combination, a main rudder, at least one auxiliary rudder adapted to adjust the latter with the aid of the current, driving mechanism for an adjustment of said auxiliary rudder comprising 35 a worm-gearing, and an intermediary gearing comprising at least two parts, namely a double cam-disc with displaced phases of the single discs and an oscillatory knee-lever in contact therewith, and adapted to 40 produce the relative movement to be executed by the auxiliary rudder with reference to the main rudder, said cam-disc serving as direction governor and adapted to be adjusted from the vessel and said knee-lever fulcrumed on said main rudder and adapted to participate in the movement 45 of the latter.

26. In a rudder arrangement for vessels and aircraft: in combination, a main rudder, at least one auxiliary rudder adapted to adjust the latter with the aid of the current, driving mechanism for an adjustment of said auxiliary rudder comprising 50 a worm-gearing, and an intermediary gearing comprising at least two parts, namely a double cam-disc with displaced phases of the single discs and an oscillatory knee-lever in contact therewith, and adapted to 55 produce the relative movement to be executed by the auxiliary rudder with reference to the main rudder, said cam-disc serving as direction governor and adapted to be adjusted from the vessel and said knee-lever fulcrumed on said main rudder and adapted to participate in the movement 60 of the latter.

In testimony whereof I affix my signature.

EMIL LUCHSINGER.
